UNITED STATES PATENT OFFICE.

MICHAEL JOSEPH DRISCOLL, OF CRISTOBAL, CANAL ZONE.

POISON-BOTTLE.

1,162,583.

Specification of Letters Patent. Patented Nov. 30, 1915.

Application filed September 28, 1915. Serial No. 53,080.

To all whom it may concern:

Be it known that I, MICHAEL J. DRISCOLL, a citizen of the United States, at present residing at Cristobal, in the Canal Zone, have invented a new and Improved Poison-Bottle, of which the following is a full, clear, and exact description.

The prime object of my invention is to provide a bottle that may be utilized for containing poison and so formed as to insure that its contents will be used only with deliberation, thereby preventing the accidental taking of the poisonous contents in mistake for non-poisonous substances.

In carrying out my invention I so form the bottle that it can not be made to stand on end but must rest with its cylindrical body horizontal. I provide the body with a lateral bottle neck between the ends of the bottle.

Reference is to be had to the accompanying drawings forming a part of this specification in which similar reference characters indicate corresponding parts in all the views.

Figure 1 is a partly sectional side elevation of a bottle embodying my invention; Fig. 2 is a plan view; and Fig. 3 is an end elevation.

In producing a bottle embodying my invention, the body 10, thereof is made in the form of an elongated cylinder. The body 10, is formed with closed ends 11, and said ends are convexed. At a side of the bottle,

preferably equidistant from the convexed ends 11, I form the bottle neck 12, adapted to receive any approved stopper 13, or other closure.

By the described construction the convexed ends 11, will prevent the bottle from being stood on either end and require that it be laid lengthwise. The position of the bottle neck at a side and substantially equidistant from the ends will necessarily arouse caution in a person taking up the bottle to pour its contents and the unusual positioning of the bottle that will be required to pour the contents will further serve as a reminder of the character of the bottle. Moreover, the cylindrical shape of the body will give it instability so that upon a hand contacting with the bottle, its tendency to rock will contribute to the warning of the special character of the bottle and its contents.

Having thus described my invention, I claim as new and desire to secure by Letters Patent:

A poison bottle having a cylindrical body, closed convexed ends, and a neck extending laterally from the cylindrical body between the said ends.

In testimony whereof I have signed my name to this specification in the presence of two subscribing witnesses.

MICHAEL JOSEPH DRISCOLL.
